UNITED STATES PATENT OFFICE.

CHARLES P. BRASINGTON, OF CINCINNATI, OHIO, ASSIGNOR TO THE INTERNATIONAL PRINTING INK CORPORATION, OF NEW YORK, N. Y., A CORPORATION OF OHIO.

DEVICE AND METHOD FOR CONVEYING VISCOUS SUBSTANCES.

Application filed March 23, 1928. Serial No. 264,168.

This invention relates to conveying apparatus and is particularly directed to a device for conveying viscous or tacky substances.

The invention has been developed in relation to mills for grinding viscous fluids or tacky substances and in its conception directed to an attachment device for loading the mill or feeding the substance to be ground to the rolls of the mill. This application of the invention has been especially advantageous due to the nature of the substances fed into a grinding mill.

The substance to be ground, such as ink in a viscous or tacky state, usually comprising a mixture of pigment and oil or varnish, is usually contained in tanks or drums and loaded or elevated therefrom onto the rolls of the mill. Heretofore, this operation has been manual labor, accomplished by means of a scoop and therefore necessarily, due to the nature of the substance, an extremely difficult and unpleasant task. By this manual feeding or loading operation, no arrangement has been possible for placing material in the mill in such quantity or at such rate, consistent with the capacity of the mill, with the frequent result that the mills have run empty until the operator of a group of mills completed his round.

It is therefore an object of this invention to provide a conveying device for use if desired in combination with a mill, this device driven at a speed timed to that of the rolls of the mill and adapted to provide a constant uniform feed of the substance to be ground from containers to the rolls of the mill.

Another object is to provide a device of this nature which is readily swung back or removed from one container for insertion in another container, which device elevates the substance from a point considerably below the level of the objective point.

The nature of those substances, the conveyance of which constitutes the present problem, prohibits the use of any endless carrier type of conveyor depending on a gravity discharge from the carrier as, for example, a bucket type of conveyor. Carriers elevating the substance by means of receptacles, or cavities of any sort fail because of the adhesiveness of the substance whereas the present invention utilizes that characteristic.

Therefore, another object is to provide a device which elevates a tacky or viscous substance entirely by means of the adhesion and temporary suspension of the substance to and from an endless carrier, and which permits a substantial removal of the substance therefrom by means of a scraper at the objective point.

Another object is to provide a device of this nature for use in feeding sticky substances, which is so designed as to be easily cleaned and readily removed as a unit from its position in an environment and which necessitates substantially no change in the apparatus to accommodate its attachment thereto.

Still another object is to provide means for quickly dismounting the endless carrier from its mounting and driving means.

Further objects and advantages will be more fully set forth in a description of the accompanying drawings, forming a part of this specification, in which:

Figure 1 is a side elevation of a mill showing the present invention attached thereto, and in its operative position for feeding the material from a tank to the mill rolls.

Figure 2 is a top plan view of Figure 1, further illustrating the device in its relation to a mill.

Figure 3 is a sectional view taken on line 3—3, Figure 1, showing the feeding device in enlarged detail.

Figure 4 is a sectional view taken on line 4—4, Figure 3, showing the relation of the scraper blade to the sheave and the endless carrier.

Figure 5 is a side elevation of the clutch arrangement for connecting the mill power to the feeding device.

Figure 6 is a detailed sectional view taken on line 6—6, Figure 1, detailing one of the pulleys in the foot piece for directioning the flexible endless carrier at the point where it is adapted to run through and pick up the material.

Figure 7 is a view taken somewhat similar to Figure 4 but showing the depending or leg element of the feeding device swung upwardly and supported in a sling while not in use or during an interchanging of container drums.

Figure 8 is a side view of the foot of the

device showing its adjustable mounting in relation to the carrier leg, a carrier dismounting position of the foot being shown in dot and dash lines.

5 Referring to Figures 1 and 2 of the views of the drawing, the device forming the present invention is shown attached to a mill, the mill being generally indicated at 1.

10 The particular mill shown herein, comprises, a pair of side frames 2, and a plurality of horizontally disposed rolls 3 journalled in the respective side frames, only one of the side frames being shown herein, inasmuch as they are of duplicate construction. These 15 rolls 3 are horizontally adjustable relatively for varying the degree of contact of the respective grinding surfaces thereof to properly grind the substance being fed into the mill. This adjustment is accomplished by 20 means of a handwheel 4, screw-threaded into the end wall 5 of a guideway 6, formed in each side frame. The handwheel screw engages an adjustable floating bearing block 7 of an end-roll, a block journaling each spindle 25 8 of the rolls.

30 In the mill of the type illustrated, there are three rolls used in the grinding of the substance, the Figures 1 and 2 being fragmentary views of the mill, and showing only two of the rolls. The intermediate roll is journalled in bearing blocks 9, the bearing blocks 9 being immovably secured to the frame between the outside roll bearing blocks of the series. Compression springs 10 are 35 interposed between the respective bearing blocks 7 and the block 9 for causing the floating blocks 7 to follow up the screw adjusting movement. The construction of the mill is not detailed in these drawings inasmuch as 40 all that is necessary is a series of mill rolls and the proper mounting therefor to illustrate an application of this invention.

45 Broadly speaking, the device to which this invention is principally directed, comprises, an endless carrier moved by engagement over a driving sheave and arranged for passage through a substance to be conveyed. The carrier is adaptable for feeding any substance of a viscous or tacky nature which 50 will adhere thereto and temporarily suspend therefrom. The discharge of substance at the objective point is accomplished by the engagement of the carrier with a scraper blade. The endless carrier may be of any 55 flexible formation, a plain wire or cable operating efficiently and being easy to clean, with the range of possible formation extending to chains, belts, etc.

60 Referring again in detail to the drawings, a gear 11 is shown mounted on the spindle 8 of the roll beyond the frame 2. The main shaft 13 of the device is journalled in a U-shaped frame 14, this frame being attached to the upper surface of a mill frame 2 by 65 means of a plate 15 adjustably secured to

the frame of the mill by a bolt 15^a engaging through a slot in the plate. A small sprocket gear 16 is loosely mounted on the outer end of the shaft in line with the gear secured to the roll, and a sprocket chain 17 is provided 70 as the transmission means between these two gears.

75 The shaft 13 is horizontally disposed and journalled in the respective arms of the U-shaped frame and a pulley or sheave 18 is secured to the end of the shaft 13 opposite to the end carrying the gear 16. This pulley or sheave has a fairly wide face and is provided centrally with a peripheral groove 19. An endless carrier 20 is tracked in the groove 80 and moves around a pair of pulleys 21—21 mounted on a foot 22 attached to the outer end of the leg 23 suitably secured to the shaft 13. This endless carrier may be formed of wire, chain, belt or a cable of any sort. It 85 has been found that a wire cable is preferable for this purpose, inasmuch as it is easily cleaned and the tacky fluid or viscous substance about to be ground adheres thereto sufficiently for the purpose of the feed. 90

95 The power to the sheave 18 is controlled by means of a toothed clutch member 24 keyed to the shaft 13 and translatable thereon between the outer face of one of the arms of the frame 12 and the inner toothed face 25 of the small sprocket gear 16. The sprocket gear 16 is loosely mounted on the shaft but held against longitudinal movement or translation thereon by means of collars 26 pinned to the shaft at each side of the gear. The 100 teeth of the adjacent faces of the gear 16 and the clutch member 24 are engaged by means of the translation of the clutch member through a pivot lever 27 vertically mounted on a pin 28 traversing a pair of arms 29 extending from the arm of the U-shaped frame. This lever has a ball portion 30 formed at 105 its inner end engaging in a concentric groove 31 in the clutch element 24 and has a handle formed on its outer or upper end. 110

115 The carrier support or leg 23 of the device extends radially from the shaft 13 and is mounted on a stud extension 32 as a part of a collar 33 loosely rotatably mounted on the shaft between the sheave and an arm of the frame. The stud telescopingly 120 engages in a tubular end 34 of the leg 23. Rotation of the leg in relation to the stud is prevented by means of a collar 35 secured on the stud adjacent the collar portion by means of a screw 36, this collar 35 having a pin 37 extending from its outer face into a slot 38 formed longitudinally of the leg and in the wall of the tubular portion.

125 The lower end of the leg is provided with a squared head 39 and the foot 22 is adjustably secured to the side of the squared portion by means of a screw 40. The foot 22 is of curved formation and as shown in Figure 1, its outer ends extend downwardly below the lower or 130

headed end of the leg. The pulleys 21 are secured to the respective ends of the foot, each of the pulleys being vertically disposed and mounted on a bolt 41, screw-threaded into the 5 face of the leg opposite to the face engaging the squared or headed lower end of the leg. The bolts comprise (see Figure 6) a head, a plain portion and a shoulder engaging the side of the foot and a screw-threaded portion 10 extending through the foot and being provided with a nut on the opposite side for clamping it to the foot.

When in operative position, these pulleys are disposed substantially in the same plane, 15 and the endless carrier 20 extending from the driving sheave passes over both pulleys and under the foot.

In order to make it possible to easily remove the carrier from its engagement with 20 the pulley, it is provided that the foot may be swung after loosening the screw 40 holding it to the leg and moved within a range of movement prescribed by a pin 42 extending through an upper corner of the squared end 25 of the leg at such point as to be engaged by the upper face of the foot after certain movement in either direction. By this arrangement, the endless carrier may be tightened around the sheave and the carrier holds the 30 leg in its telescopic relation to the stud 32, so that upon removal of the carrier by rotation of the foot on its screw, it is possible to disassemble the leg from the device.

Inasmuch as the leg is attached to the loosely mounted collar it is possible to swing the 35 leg and carrier in an arc described from the center of the shaft. This movement is provided in order that the foot and leg carrying the lower end of the endless connector may be 40 swung upwardly from the container in which the mechanism is operated during an interchangement of containers or when the device is not in use.

The pivotal mounting of the foot provides 45 for setting the foot in horizontal plane despite various inclinations of the leg due to variation in difference between the elevations of the substance to be fed and the objective point. After the foot is set the carrier is 50 drawn taut by sliding the collar 35 and moving the leg 23 down on the stud 32.

When the device is not in use the leg is 55 swung upwardly into engagement with a sling 43, this sling being secured to an upwardly extending post 44 formed on the arm of the frame adjacent the sheave. The post receiving surface of this sling is disposed beyond dead center so that the leg and the mechanism attached thereto will lie in the sling due to 60 the action of gravity as shown in Figure 7.

A scraper blade bracket 45 is secured to the inner face of the post and extends therefrom to a point adjacent the periphery of the sheave. A scraper blade 46 is secured to this 65 bracket and extends across the face of the

pulley on the side toward the mill roll, this blade fitting fairly snug against the face of the sheave and having a circular indentation 47 therein to fit around the endless carrier. The scraper blade is inclined from this engagement with the pulley downwardly toward the mill roll, stopping short of engagement therewith. 70

A container from which the material to be ground is fed is indicated at 48 and as shown 75 herein the endless carrier travels in a horizontal plane close to the bottom of the container so that substantially all the contents may be fed therefrom. The substance and materials fed by this device may vary greatly, 80 one instance of a material adaptable for feed by this device being that of ink pigment mixed with oil or varnish. The ink material in this state is extremely viscous, having considerable adhesive qualities. 85

The endless carrier moves in a clock-wise direction around the sheave, due to the rotation of the sheave, as it leaves the surface of the substance has a coating of the substance adhering thereto. The speed at which it is 90 necessary to operate the endless carrier is of little importance except as to bringing up the proper quantity to keep the mill constantly fed. Even at the slowest speeds enough of the substance will adhere to the endless carrier to 95 cause a feed to the mill roll.

In operation, the adhesion of the material is so great that a web of the tacky or viscous substance extends considerably upward from the surface thereof in the container. As the 100 substance is brought up to the sheave in temporary suspension it is carried therearound and scraped off the sheave and carrier by means of the scraper blade 46 and thence flows slowly downwardly from the scraper blade to 105 the surfaces of the mill roll. Inasmuch as the rotation of the outer mill roll is in an inward direction or clock-wise as viewed in Figure 1, the material deposited on the roll, although deposited toward the outer face of 110 the roll is immediately carried on the surface of the roll to the grinding point between the rolls. The device as shown is attached to a side frame of the mill and the feed is consequently at one end of the mill roll. The substance thus fed moves across a space defined between the rolls and forms a pool of substance indicated at 49. 115

Having described my invention, I claim:

1. A device for conveying viscous substances, comprising, a driven endless wire, a support for said wire adapted to dispose the wire for passage through the substance to be conveyed, and means for discharging the substance from the wire at an objective point. 120

2. A device for conveying viscous substances, comprising, a driven endless flexible member presenting an entirely convex surface, a support for said carrier adapted to dispose the carrier for passage through the sub- 130

stance to be conveyed, and means for engaging the carrier for removing the substance adhering thereto and discharging the same at an objective point.

5. 3. A device for conveying viscous substances, comprising, a driven endless flexible member, a driving pulley therefor, a support for said pulley and flexible member, said support adapted to dispose said flexible member 10 for passage through the substance to be conveyed, and a discharge element disposed in relation to said pulley for removing the substance, conveyed by adhesion to the flexible member, from the pulley and flexible member.

15. 4. A device for conveying viscous substances, comprising, a power pulley and a carrier wire engaged over said pulley for deriving movement therefrom, means for guiding said carrier wire through the substance to be fed, and a scraper blade disposed in relation to said carrier wire for discharging the substance at an objective point.

20. 5. A device for conveying viscous substances, comprising, a driven endless flexible carrier, a frame, a driving sheave for the carrier mounted on said frame, a support for said carrier adapted to dispose the carrier for passage through the substance to be conveyed, 25 said carrier support having its end pivotally secured to the sheave mounting for swinging the carrier relative to the substance to be conveyed, and means for discharging the substance from the conveyor at an objective point.

30. 6. A device for conveying viscous substances, comprising, a frame, an endless flexible carrier, a driving sheave for the carrier, said sheave having its shaft journalled in said frame, a support for said carrier adapted to define the carrier movement for passage thereof through the substance to be conveyed, said support pivotally secured to the shaft of the driving sheave, said support of telescopic formation for extending the same, and means for setting the support in adjusted extended position, whereby the carrier is mounted in taut condition.

35. 7. A device for conveying viscous substances, comprising, a frame, an endless flexible carrier, a rotary driving member for the carrier, said rotary member having its shaft journalled in said frame, a support for tracking said carrier adapted to define the carrier movement for passage thereof through the substance to be conveyed, said support pivotally attached to the shaft of the rotary member, said support comprising a collar loosely mounted on the shaft and having a radial stud extension thereon, and an extension member in telescoping engagement with said stud, and means for setting the support in extended position, whereby the carrier is mounted in taut condition.

40. 8. A device for conveying tacky substances,

comprising, a frame, an endless flexible carrier, a pulley for driving said carrier mounted in said frame, a support for defining the movement of the carrier from the substance to be fed to the sheave, and a scraper blade disposed tangent to the pulley periphery, said blade engaged around the carrier and against the pulley periphery for removing and discharging the substance adhering thereto and brought thereto from a source by temporary suspension from the carrier.

9. A device for conveying tacky substances, comprising, a frame, an endless flexible carrier, a pulley for driving said carrier mounted in said frame, a support for defining the movement of the carrier from the substance to be fed to the pulley, and a scraper blade adjacent the pulley periphery, said blade removing and discharging the substance adhering to the pulley periphery and brought thereto from a source by temporary suspension from the carrier.

10. A device for conveying tacky substances, comprising, a frame, an endless flexible carrier, a driving pulley for said carrier having its shaft journalled in said frame, a downwardly extending support for defining the course of movement of the carrier relative to the source of substance, a foot pivoted to said support and adjustable in a vertical plane, idler pulleys mounted at each end of the foot for disposing the carrier under the foot, and means for setting the foot in an adjusted position, whereby said foot is positioned to dispose the carrier portion between the idler pulleys in a substantially horizontal position regardless of the degree of inclination of the support.

11. A device for conveying tacky substances, comprising, a frame, a driving sheave having its shaft journalled in said frame, an endless flexible carrier drivingly engaged with said sheave, a leg extending radially from said shaft and pivotally attached thereto, a foot pivotally mounted on the lower end of said leg, an idler pulley mounted at each end of said foot, said leg and foot forming a support for said carrier, said carrier being disposed around said idler pulleys for defining the course of movement of said carrier relative to the source of substance, said foot thereby adjustable to a desired plane regardless of the inclination of the leg, means for extending the leg for tightening the carrier, and a discharge element disposed in relation to said sheave and carrier for removing and discharging the substance adhering thereto at an objective point.

12. A conveyor for tacky fluids, comprising, an endless flexible member having convexly contoured surface to which the fluid is adapted to adhere, a mounting for said member adapting it to be passed continuously between a point within the fluid and the point of desired delivery, means for driv-

ing said flexible member, and a discharge member placed in the proximity of said flexible member adjacent to the point of delivery, said member adapted to remove the fluid 5 adhering to said convexly contoured surface of the flexible member.

13. The method of transporting a tacky fluid, said method, comprising, passing an endless wire therethrough to which said fluid 10 is adapted to adhere, and transporting said fluid in suspension therefrom.

14. The method of elevating a tacky fluid, said method, comprising, passing continuously a flexible endless member therethrough, 15 said member having an entirely convex surface from which appreciable quantities of said fluid are adapted to suspend themselves temporarily.

15. The method of elevating a tacky fluid, 20 said method, comprising, passing a wire therethrough to which the fluid is adapted to

adhere, and driving said member at such speed that the said adhering fluid reaches the desired delivery point before the termination of the temporary suspension resulting from 25 said adhesion.

16. The method of transporting a viscous substance, said method, comprising, suspending predetermined quantities thereof from a wire driven therethrough. 30

17. The method of transporting a viscous substance, said method, comprising, adhesively suspending quantities thereof from the entirely convex surface of a flexible endless member driven therethrough at a speed 35 adapted to deliver a desired quantity of said suspended substance at the objective point before the termination of said suspension.

In witness whereof, I hereunto subscribe my name.

CHARLES P. BRASINGTON.
